(57) CLAIM

The ornamental design for a projection television set, as shown and described.

DESCRIPTION

FIG. 1 is a front, top and right side perspective view of a projection television set, showing our new design;

FIG. 2 is a perspective view thereof with a door of the operation section and that of the storage section opened;

FIG. 3 is a top plan view thereof;

FIG. 4 is a right side elevational view thereof; a left side elevational view being a mirror image thereof;

FIG. 5 is a front elevational view thereof;

FIG. 6 is a bottom plan view thereof; and,

FIG. 7 is a rear elevational view thereof.
